UNITED STATES PATENT OFFICE.

WILLIAM M. NECKERMAN, OF YOUNGSTOWN, OHIO.

PIPE-MAKING APPARATUS.

1,312,197.

Specification of Letters Patent. Patented Aug. 5, 1919.

Continuation in part of application Serial No. 597,193, filed December 14, 1910. This application filed July 2, 1912. Serial No. 707,285.

To all whom it may concern:

Be it known that I, WILLIAM M. NECKERMAN, a citizen of the United States, residing at Youngstown, in the county of Mahoning and State of Ohio, have invented new and useful Improvements in Pipe-Making Apparatus, of which the following is a specification.

My invention relates to apparatus for manufacturing metal pipes from heated skelp.

In the manufacture of butt-weld pipes by the common method, an assistant called a hook-runner connects the pipe-drawing tongs by means of a hook to the endless draw-chain on the draw-bench after the welder has fastened the tongs to the skelp. The hook-runner follows the hook toward the rear of the draw-bench until the skelp has been pulled entirely through the welding-die, whereupon he disconnects the hook from the draw-chain and the tongs, and returns to front of the draw-bench to repeat the operation. In the performance of his duties, the hook-runner is liable to be severely injured from various causes. As there are several hook-runners for each draw-bench, their wages amount to a large sum. It is the principal object of my invention to provide means for automatically connecting the tongs to the draw-chain and automatically disconnecting the same from the tongs, thereby dispensing entirely with the hook-runners.

Another object of my invention is to provide means whereby the welded pipe may, after the tongs have been disconnected from the draw-chain, be allowed to continue its rectilinear course beyond the rear end of the draw-bench, or be guided laterally away from the draw-bench.

Referring to the accompanying drawings, Figure 1 is a plan view of an apparatus embodying one form of my invention, parts being broken away and in section; Fig. 2, a longitudinal vertical section along the side of the draw-chain; Fig. 3, a vertical cross-section on the line III—III, Fig. 2; Fig. 4, a plan view of a portion of the draw-chain with one of the tongs-pulling dogs or holders; Fig. 5, a section of a portion of the draw-bench, showing the operation of one of the tongs-pulling dogs and the tripper therefor when the pipe with the tongs attached is to be guided laterally away from the draw-bench; and Fig. 6, a side eleva-

tion of the chain-guiding roller at the rear of the draw-bench. Fig. 7, is a plan of a portion of a drawing-chain differing from that shown on Fig. 4.

On the drawings, 1 is a furnace for heating the skelp to a welding heat, there being in the furnace the front opening 2, through which the skelp are drawn by the tongs 3.

4 is a draw-bench of usual construction except as to details presently to be described. The bed or top of the draw-bench has a pair of parallel longitudinal vertical flanges 5 rising therefrom to provide the sides of a channel in which the draw-chain 6 may travel and be guided as it is drawn rearwardly along the draw-bench by the sprocket-wheel 7 on the shaft 8, driven by any suitable means. The flanges 5 have secured to their upper edges the strips or flanges 9 which overlap the sides of the draw-chain, having a longitudinal space in which the upper or tongs-pulling member of the forked dog 10 may travel.

The dog 10 is a bell-crank lever having its angle pivoted about one of the pivots 11 of the draw-chain. Preferably the angle between the members or arms of the dog or lever 10 is somewhat greater than a right angle, so that, when the horizontal member 12 rides on the top face of the liner 13, which lies on the bottom of the chain-guide channel, the upstanding member 14, which extends above the flanges 9, will be inclined slightly in the direction of the travel of the draw-chain, in order to more securely hold the knob or headed end 15 on the tongs from rising out of the vertical open slot 16 in the upper end of the member 14, and to prevent the dog from rotating when passing over the slot 17 under conditions to be described hereinafter. The member 12 has the upper face of its rear end cut out so that it may lie between the liner 13 and the chain-pivot next behind the one about which it is pivoted, so that the dog cannot be oscillated toward the rear of the bench.

18 represents a lever pivoted intermediate of its ends on the pivot 19 on the draw-bench. This lever lies diagonally over the draw-chain and the slot 17. The lower edge of the lever is provided with a horizontal tripping plate 20 extending toward the front of the draw-bench, and having its free or front edge arranged to engage the member 14 between the draw-chain and the knob 15 on the tongs. The end of the lever 18, not

provided with the tripper or tripping plate 20, is connected by the link 21 to the arm 22 of the rock-shaft 23, actuated by the lever 24 near the rear end of the bench, but the lever 5 18 may be operated from any proper location and by variously arranged means. The lever 18 above the tripper 20 is a flat piece of metal arranged to be engaged by the knob 15 of the tongs at the time of the release of 10 the tongs from the member 14, this lever 18 acting as a guide to direct the tongs and the attached pipe diagonally away from the chain and draw-bench.

25 is the ordinary welding-bell or die 15 resting on the bell-holder 26 at the front of the draw-bench.

27 and 28 are inclined guides supported on the standards 29 and 30 at opposite sides of the chain, and arranged to guide the tongs 20 down into position for the slot 16 in the member 14 to receive the tongs just back of the knob or headed end 15. The guides 27 and 28 are pivoted to their respective standards, and have their lower ends in line with 25 the paths of the branches of the member 14 of the dog 10 so that the tongs will be guided into line with the slot 16.

The chain passes from the rear end of the draw-bench over the roller 32, having there 30 in the annular groove 31 sufficiently deep to permit the member 12 of the dog 10 to pass while the links of the chain ride on the annular shoulders 33 at the sides of the groove 31.

35 The chain passes from the roller 32 over the sprocket-wheel 7 and then runs on the chain-guide 34 beneath the bed of the draw-bench. This chain-guide is preferably in the form of a trough or channel which leads 40 the chain 6 forwardly to the roller 35 over which the chain is guided to the top of the draw-bench.

The chain 6 is provided with a sufficient 45 number of dogs 10 to engage the tongs as fast as the welder secures the tongs to the skelp.

50 The operation of my invention is as follows: The draw-chain is set in motion. The welder fastens the tongs 3 to the front end of one of the skelp 36, slips the bell 25 over the end of the tongs 3, slides the bell down the tongs until the bell is in front of the bell-holder 26, and drops the tongs between the guides 27 and 28, or throws the tongs against 55 the guides, from which the knob 15 of the tongs drops into the path of one of the dogs 10. The first dog 10 that rises from the inclined bed 37 just back of the roller 35 receives the end of the tongs in the slot or fork 60 16 with the knob or headed end 15 in front of the member 14. The inclined bed 37 brings the dogs 10 up gradually into the plane of the tongs lying on the chain and into tangential engagement with the tongs, 65 and thereby prevents the tongs-engaging

dogs of the draw chain from knocking the tongs aside as the dogs enter the plane of the tongs. It has been found that if this incline 37 be dispensed with and the roller 35 be brought up to the plane of the bed of the draw bench, the dogs traveling up 70 around the roller will strike upward blows on the tongs and flip them off the chain. The resistance offered by the skelp 36 in the bell 25 tends to rotate the dog 10 from right 75 to left, but the contact of the member 12 with the bed of the chain-guide channel and the engagement of the links to which the dog is secured, with the overhanging flanges 9 prevent the rotation of the dog. The pipe 80 is drawn entirely through the bell on the chain before the dog reaches the slot, so that there is no tendency of the dog to overturn the slot. If the dog should rotate into the slot it can be turned back before it reaches 85 the end of the slot. When the skelp has been drawn entirely through the bell, the resultant pipe 38 with the tongs attached rides on the chain toward the rear end of the bench, and if the lever 18 has been thrown 90 by the lever 24 to the dotted position (Fig. 1), the pipe and tongs will be carried by the chain not only to the rear of the draw-bench, but also through the guide 39 and into the pass of the sizing rolls 40 situated close to 95 the end of the bench and in line with the bench 1 when in its central position (Fig. 1). When the dog 10 reaches the roller 32, the member 12 is free to enter the groove 31 and the dog 10 begins to descend and rotate from 100 right to left, and release the tongs, which with the pipe pass directly through the guide 39 and into the pass of the rolls 40. The chain rides on the guide 34 with the members 12 of the dogs 10 extending upwardly. 105 When the dogs arrive close to the roller 35, the members 12 engage with the horizontal pin 41 which rotates the dog so as to pass over the roller 35 with the member 12 in line with the adjacent chain-links. 110

The pipe has entirely left the bell and is on the chain before the dog reaches the slot, so that there is no tendency of the dog to overturn in the slot. If the dog should rotate in the slot, no harm will be done, as it 115 will be turned back before it reaches the end of the slot.

If it is desired to reheat the pipes and repeat the welding operation, or if it is desired for any other reason to have the pipes 120 discharged laterally from the draw-bench, the lever 24 is actuated so as to throw the lever 18 across the draw-bench, as shown in Figs. 1, 2, and 5. The operation proceeds as described until the dog 10 arrives at the 125 slot 17. The member 14 of the dog 10 engages the tripping plate 20, below the knob 15 on the tongs and causes the dog to rotate from right to left, so that the member 12 swings into the slot 17 and the member 14 130

swings down away from the tongs so as to pass beneath the lever 18, as shown in Fig. 5. After the dog 10 has passed the lever 18 sufficiently far to enable the member 14 to rise without engaging the lever 18, the member 12 engages the rounded rear end of the slot 17 (Fig. 5), which restores the dog to its normal position, but the slot 17 may be left open to the rear of the bench if preferred.

Fig. 7 shows the chain 6^a having its outer links with inturned bosses 42 in openings in the inner links, the pins 11^a pass through the bosses and hold the links from relative lateral movement. The dog 10^a is pivoted on certain of the bosses 42, instead of the pins 11^a.

The chain-guide 34 is to be preferred to idle rollers. The swinging dogs 10 would engage each of the rollers and make considerable noise and give severe shocks to the draw-chain. The trough 34 provides a comparatively noiseless return of the chain with a minimum of noise and of shock to the chain and dogs.

This application is a continuation in part of my application, Serial Number 597,193, filed December 14, 1910.

I claim—

1. In a pipe-drawing apparatus, the combination of a welding die, skelp-engaging tongs and a draw bench having an endless draw chain having travel thereon, one or more forked dogs having endless travel with the draw chain and adapted to engage the end of said tongs while the chain is traveling and pull the skelp through the welding die, and centering means for the tongs arranged to position them in the path of the dog or dogs, substantially as described.

2. In a pipe-drawing apparatus, a draw-bench, an endless draw-chain having travel thereon, a welding die, skelp-engaging tongs, a dog having endless travel with the draw-chain and provided with a fork to engage the end of said tongs and pull the skelp through the welding-die, and means for causing the dog to be released from the tongs.

3. In a pipe-drawing apparatus, a draw-bench with a slot therein, an endless draw-chain having travel over the slot, a welding-die, a skelp engaging device, a dog having endless travel with the draw-chain and provided with a member for engaging the skelp-engaging device and pulling the skelp through the welding-die, the dog being provided with a member having travel opposite the said slot and arranged to engage

the draw-bench to prevent the release of the dog from the skelp-engaging device, and means for forcing the first member away from the skelp-engaging device, and the second member into the slot.

4. In a pipe-drawing apparatus, a draw-

bench, an endless draw-chain having travel on the draw-bench, a welding-die, a skelp engaging device, and a dog having endless travel with the draw-chain and provided with a member for engaging the skelp-engaging device and pulling the skelp through the welding-die, the dog being pivoted to the chain and provided with a member arranged to prevent the release of the dog from the skelp-engaging device.

5. In a pipe-drawing apparatus, a welding die, a skelp-engaging device, an endless traveling draw-chain, a draw-bench on which the chain travels, there being a slot in the draw-bench beneath the chain, a bell-crank dog pivoted to the draw-chain, one member of the dog being arranged to engage with the draw-bench channel-guide and the other member being provided with means for engaging the skelp-engaging device and pulling the same through the welding die, and means to prevent the draw-chain from rising from the said slot permitting one member of the dog to rotate through the same when the other member is released from the skelp-engaging device.

6. In a pipe-drawing apparatus, a welding die, a skelp-engaging device, an endless traveling draw-chain, a draw-bench provided with a channel-guide to receive the chain, a bell-crank dog pivoted to the draw-chain, one member of the dog being arranged to rest on the channel-guide, and the other member being provided with means for engaging the skelp-engaging device and pulling the same through the welding die, and a roller at the rear end of the bench, over which the chain travels, said roller having an annular groove to receive the first member of the dog.

7. In a pipe-drawing apparatus, welding-tongs, an endless traveling draw-chain, a draw-bench on which the chain travels, a bell-crank dog pivoted to the chain, one member of the dog being arranged to engage with the draw-bench and the other member being provided with means for engaging the tongs, a chain-guiding roller at the rear end of the draw-bench, the chain having downward travel from the said roller and the roller having in line with the first member of the dog a circumferential groove to receive the said first member as the dog travels downwardly with the chain.

8. In a pipe-drawing apparatus, the combination of a welding die, skelp-engaging tongs, and a draw bench having an endless draw chain having travel thereon, means having endless travel with the draw chain and adapted to engage the ends of said tongs while the chain is traveling and pull the skelp through the welding die, and continuously operating means for preventing the tongs-engaging means of the draw chain from knocking the tongs aside as they enter

the plane of the tongs lying on the chain, substantially as described.

9. Pipe-drawing apparatus having tongs by which the pipe skelp is gripped and drawn through the welding bell, comprising a draw bench having an endless chain, means for actuating said chain, means on the chain adapted to automatically engage the tongs reins and draw skelp gripped by the tongs lengthwise over the draw bench, and centering mechanism arranged to position the tongs centrally in the path of the chain-engaging means, substantially as described.
10. Pipe-drawing apparatus having tongs by which the pipe skelp is gripped and drawn through the welding bell, comprising a draw bench having an endless chain thereon, means for continuously driving the chain, means automatically engaging with the tongs reins adapted to grapple with the reins when the tongs are placed in position on the draw bench and draw skelp in the grip of the tongs lengthwise over the draw bench, the said apparatus being arranged to prevent the tongs-engaging means from knocking the tongs aside as they enter the plane of the tongs, and centering means to position the tongs centrally in the path of the tongs-engaging means, substantially as described.

11. In a pipe-drawing apparatus, the combination of a welding die, skelp-engaging tongs, and a draw bench having an endless draw chain having travel thereon, means having travel with the draw chain for engaging the tongs to pull the skelp through the welding die and means coöperating with the tongs-engaging means to automatically release the tongs after the skelp has been pulled through the welding die; substantially as described.

12. In a pipe-drawing apparatus, the combination of a welding die, skelp-engaging tongs, and a draw bench having an endless draw chain having travel thereon, means having endless travel with the draw chain for engaging the tongs to pull the skelp through the welding die, and centering means acting automatically to position the tongs in the path of the tongs-engaging means; substantially as described.

13. In a pipe-drawing apparatus, the combination of a welding die, skelp-engaging tongs, and a draw bench having an endless draw chain having travel thereon, means having endless travel with the draw chain for engaging the tongs to pull the skelp through the welding die, and a downwardly

converging guide into which the welder may drop the tongs for positioning the tongs in the path of the tongs-engaging means; substantially as described.

14. In a pipe-drawing apparatus, the combination of a welding die, skelp-engaging tongs, and a draw bench having an endless draw chain having travel thereon and upon which the tongs are dropped by the welder, means having endless travel with the draw chain for engaging the tongs to pull the skelp through the welding die, and means acting automatically to position the tongs dropped by the welder in the path of the tongs-engaging means; substantially as described.

15. In a pipe-drawing apparatus, the combination of a welding die, skelp-engaging tongs, and a draw bench having an endless draw chain having travel thereon, means having endless travel with the draw chain and adapted to engage the ends of said tongs while the chain is traveling and pull the skelp through the welding die, said parts being constructed and arranged to automatically prevent the tongs-engaging means of the draw chain from knocking the tongs aside as they enter the plane of the tongs lying on the chain; substantially as described.

16. In a pipe-drawing apparatus, the combination of a welding die, skelp-engaging tongs, and a draw bench having an endless draw chain having travel thereon, means having endless travel with the draw chain for engaging said tongs to pull the skelp through the welding die, and means for leading the chain along a gradual incline into the plane of the tongs lying on the chain so as to prevent the tongs-engaging means from knocking the tongs aside; substantially as described.

17. In a pipe-drawing apparatus, the combination of a welding die, skelp-engaging tongs, and a draw bench having an endless draw chain having travel thereon, and means having travel with the draw chain and acting automatically to engage the tongs and pull the skelp through the welding die and coöperating means acting automatically to release the tongs after the skelp has been pulled through the welding die; substantially as described.

Signed at Youngstown, Ohio, this 20th day of June, A. D. 1912.
